DESIGN FOR A HAIR TRIMMER

Cyril P. Zurlinden, Rocky River, Ohio

Application January 13, 1947, Serial No. 136,114

Term of patent 14 years

(Cl. D22—3)

To all whom it may concern:

Be it known that I, Cyril P. Zurlinden, a citizen of the United States, residing at Rocky River, in the county of Cuyahoga and State of Ohio, have invented a new, original, and ornamental Design for a Hair Trimmer, of which the following is a specification, reference being had to the accompanying drawing, forming part thereof.

Fig. 1 is a front elevation of a hair trimmer, showing my new design;

Fig. 2 is a front perspective view thereof;

Fig. 3 is a rear elevation thereof;

Fig. 4 is a rear perspective view thereof; and
Fig. 5 is a top plan view thereof.

I claim:

The ornamental design for a hair trimmer, as shown.
